W. J. FISHER

BOILER

Filed March 8, 1924

William J. Fisher

By Walter W. Burns

Attorney

UNITED STATES PATENT OFFICE.

WILLIAM J. FISHER, OF YORK, PENNSYLVANIA, ASSIGNOR TO A. B. FARQUHAR CO. LTD., OF YORK, PENNSYLVANIA, A LIMITED PARTNERSHIP OF PENNSYLVANIA.

BOILER.

Application filed March 8, 1924. Serial No. 697,905.

This invention relates to boilers of the internal furnace tubular type, and has particular relation to the inner construction of the rear combustion chamber thereof.

5 The primary object of this invention is the provision of an improved lining for the rear combustion chamber of an internal furnace tubular boiler.

Another object of this invention is the 10 provision of an improved metallic lining for the rear combustion chamber of such a boiler.

Another object of my invention is the provision of an improved metallic sectional 15 perforated lining for the rear combustion chamber of such a boiler.

Another object of my invention is the provision of an improved means for securing 20 doors to the end of combustion chambers of certain types of boilers.

Another and further object of my invention is to provide an improved means for securing the lining to the combustion chamber wall, which means will minimize the 25 conduction of heat from the lining to the wall.

Other and further objects will be apparent, from the specification, to those skilled in the art.

30 Referring to the drawing wherein I have illustrated a preferred embodiment of my invention:

Fig. 1 is a perspective view of my invention as applied to a boiler showing the doors 35 of the rear combustion chamber open;

Fig. 2 is a longitudinal sectional view of a boiler having my invention applied thereto, and

Fig. 3 is a fragmental detail view of the 40 outside of the boiler showing the side of the boiler at the rear combustion chamber end.

Like reference characters refer to similar parts throughout the several views.

In the drawing, 10 designates the shell of 45 the boiler, 11 the steam dome and 12 the smoke stack.

The numeral 15 designates the rear combustion chamber, 16 the fire box or internal furnace, and 17 the tubes. The fuel is 50 placed in the fire box 16. The smoke and hot gases pass to the right, as shown in Fig. 2 into the rear combustion chamber 15 and return through the tubes 17 to the stack 12 from whence they escape into the air.

All of the foregoing described structure is 55 old and well known in the art.

The outer end of the rear combustion chamber is covered with a pair of doors 18, 19 which are suitably hinged as shown on Fig. 3. Hinge plates 40, 41 are provided 60 and are arcuate at their outer edges to conform to the cylindrical shell of the boiler and are provided with suitable spaced lugs as shown at 41^a on Fig. 3. The doors 18, 19 are provided with suitable similarly 65 spaced lugs 41^b cast therewith for cooperation and coaction with the lugs 41^a. A bolt 41^c passes through the lugs 41^a and 41^b and constitutes, therewith, the hinge. The lugs 41^b are spaced so that they will rest, each 70 on its corresponding lug 41^a.

The rear combustion chamber at its outer and cylindrical side and at its outer end, is provided with a suitable metal lining which I preferably make of cast iron and in sections. 75

The upper portion is made preferably in two sections 25, 26 as shown in Fig. 1. These two sections are preferably flat and are located on a lower level than the steam space 80 in order to protect the end of the boiler at this point. The sections 25 and 26 are provided, respectively, with flanges 25', 26' to co-operate with and overlap adjacent sections, thus providing for expansion and easy 85 installation. These sections 25, 26 are held in spaced relation to the cylindrical shell 10 of the boiler by suitable spacing lugs 25^a, 26^a, 25^b, 26^b, of which there are two each for each plate. These spacing lugs 90 may be made separate from or integral with their respective sections. I prefer, however, to make them integral and have so shown them.

Suitable bosses 25^e, 26^e are provided for 95 the respective sections and are integral therewith. These bosses are provided with threaded studs 25^d, 26^d cast therein. These studs 25^d and 26^d, pass through the outer shell of the rear combustion chamber, where 100 nuts 25^e and 26^e hold them in place.

Spaced around the boiler from the section 26 are other segmental sections which conform to the cylindrical surface of the rear combustion chamber, but in spaced relation therefrom. These sections I have designated 30, 31, 32, 33, 34, 35 and 36. Each 105 of these sections is provided with an over-

lapping flange corresponding to the flanges 25' and 26' and are in position to overlap the adjacent sections. Each of these sections is also provided with suitable means for holding the sections in a spaced relation from the outside wall of the rear combustion chamber. I have shown spacers such as the blocks or lugs 30^a, 32^a, 33^a, 34^a, for the respective sections to prevent contact with the shell. I also provide bosses for the respective sections as shown at 32^c and 33^c and cooperating studs 32^d and 33^d, similar to the studs 25^d and 26^d, to hold the sections in place.

15 I have found that a construction which is very satisfactory is one in which the sections 25, 26, 30, 31, 32, 33, 34, 35, 36 are each provided with two bosses with their corresponding studs to hold the plates in position and are so constructed that the bosses will be arranged on a line parallel to the axis of the boiler and spaced from the end of their respective sections. It is to be noted that the lugs and bolts furnish 20 very little metallic cross-section through which heat can be conducted.

25 Fixed to the doors 18 and 19, respectively, are the liner sections 37 and 38. One of these sections, as 38, is provided with 30 an overlapping flange, as shown at 39, for cooperation with the adjacent edge of the complementary section 37.

35 The upper edge of the sections 37, 38 are of a height to pass under the sections 25, 26, the latter extending over the sections 37, 38 when the doors are closed.

40 These sections 37 and 38 are provided with spacing lugs, as shown at 37^b, similar to the lugs 25^a, 26^a and are shown as being integral with the door. Studs 37^d, 38^d are provided with suitable bosses as indicated at 37^e in Fig. 2 and secure the sections 37, 38, respectively, to their doors.

45 The sections 37 and 38 are provided, respectively, with integral extensions 37^e, 38^e which extend from the main bodies of the sections at such an angle that they will clear the hinge plates 40, 41 when the doors are closed. These extensions 37^e, 38^e have arcuate edges which, when the doors are closed, will be in close proximity to the sections 30, 31, 32 and 36, 35 and 34 respectively.

50 In order to prevent warping, each of the lining sections 25, 26, 30, 31, 32, 33, 34, 35, 36, 37 and 38 is preferably perforated as shown in the drawing.

55 It is thus clear that I have provided an efficient rear combustion chamber lining which from its construction will protect the shell of the rear combustion chamber, is 60 easy to install and which has provision for

expansion and contraction and is so constructed as to permit a minimum of warpage due to temperature changes.

65 While I have shown and described in detail an embodiment of my invention, I desire to have it understood that I do not limit myself to the exact showing and that modifications and changes may be made without departing from the spirit of my invention and within the scope of the appended claims.

70 Having described my invention, what I claim is:—

75 1. A boiler having a combustion chamber having an air cooled outside wall, a lining therefor, the lining being spaced wholly from the wall of the combustion chamber and means for holding the lining in position in spaced relation to the combustion chamber wall, the space between the lining and wall being co-extensive with the lining, said means having very small contacting surface with the wall whereby the conduction of heat from the lining to the outer wall is minimized, the upper portion of the lining extending across the chamber adjacent the level of the lower portion of the steam space of the boiler.

80 2. A boiler having a combustion chamber, a metallic lining therefor, the lining being constructed in complementary sections and spaced from the wall of the combustion chamber, the space between the lining and wall extending throughout the axial length 85 of the lining and means for holding the lining in position in spaced relation to the combustion chamber wall, said means being of a shape and so placed as to permit of a free air or gas communication between the 90 spaces outward of adjacent lining sections, the upper lining sections extending across the chamber adjacent the level of the lower portion of the steam space of the boiler.

95 3. A boiler having a rear combustion chamber, hinged doors for closing the end thereof, a lining for the rear combustion chamber, said lining comprising perforated sections about the cylindrical side and perforated sections on the doors, the sections 100 about the cylindrical side having portions overlapping adjacent respective sections, the door sections cooperating with the sections about the cylindrical side of the rear combustion chamber, the door sections having 105 portions at an angle to the main body thereof and means for spacedly holding the lining sections from the wall and doors, respectively.

110 In testimony whereof I hereunto affix my 115 signature.

WILLIAM J. FISHER.
